UNITED STATES PATENT OFFICE.

WILLIAM H. KNIEP, OF ST. LOUIS, MISSOURI, ASSIGNOR TO GRAHAM PAPER COMPANY,
OF ST. LOUIS, MISSOURI, A CORPORATION OF MISSOURI.

MARKETING BAG.

1,419,739.

Specification of Letters Patent. Patented June 13, 1922.

Application filed June 17, 1920. Serial No. 389,779.

To all whom it may concern:

Be it known that I, WILLIAM H. KNIEP, a citizen of the United States, residing at the city of St. Louis, in the State of Missouri, 5 have invented certain new and useful Improvements in Marketing Bags, of which the following is a specification.

This invention is a marketing bag and has, for its object the provision of means for 10 permitting the person using it to inspect its contents without removing such contents.

A shopper or person engaged in marketing generally has a variety of items on the mind and needs easy access to the contents 15 of such a bag as this to determine whether or not a certain article has been purchased. In practice, it has been found not enough to be able to put the hand in from the top and to move the contents around and to look at 20 them from the top. This invention is auxiliary thereto and supplies the needed last step of efficiency that enables easy and convenient inspection of the contents of such a receptacle.

25 In the accompanying drawings forming part of this specification, in which like numbers of reference denote like parts wherever they occur,

Figure 1 is a perspective view of this bag, 30 showing one form of transparent window;

Figure 2 is a similar view showing a different form of window;

Figure 3 is a similar view showing a third form of window;

35 Figure 4 is a sectional view through the wall containing such window in the bag and showing the transparent closure for the window, and

Figure 5 is a perspective view of a grocer's 40 or green-grocer's "tut" having a window therein.

The bag 1 may be of any form, size, or material. The window 2 may be of any form or size, and may be placed in any location on 45 the bag 1. There may be as many windows 2 as desired, as, for instance, there may be a plurality of the same in the front wall where window 2 is shown in the drawings. There may, also, be one of such windows or 50 a plurality of such windows in any of the other walls of bag 1, or, if desired, in all the said walls.

The window 2 will be closed with a piece 55 of transparent material 3 which may be of any size or shape, and the same will be attached to bag 1 in any suitable manner, but

preferably by adhesive 4. For the sake of cheapness the said transparency 3 will preferably be of paper.

The transparency 3 may be of any material and it may be attached at part of its side edges or at all of its periphery by the adhesive 4 to either the inside or outside of the bag, but preferably to its inside. In case glass or mica or celluloid or the like were 60 used as the closure or transparency 3, a pocket or other means (not shown in the drawings) will be necessary to attach it in place, instead of the adhesive 4.

Constructed as thus described, the bag as 70 a whole is efficient, cheap, and convenient, and fills a long-felt want for the uses and purposes above-described.

Another use to which this invention may be put is in "tuts" or containers such as are 75 used by grocers, green-grocers, and other merchants, to contain goods put up by them for sale, especially in self-service grocery stores and the like, affording prospective customers an opportunity to look through the 80 window in the "tut" to see the contents of the bag. This does away with the necessity of labels or writing on the bags to denote their contents, and is a great convenience to customers. It allows the merchant to put 85 up in advance as many packages of any article as he desires. He then sets them out on a shelf or other place where customers can see them. The customers look through the window 2 covered by the transparency 3. 90

Having thus described this invention, I hereby reserve the benefit of all changes in form, arrangement, order, or use of parts, as it is evident that many minor changes may be made therein without departing from the 95 spirit of this invention or the scope of the following claim.

I claim:

An open topped bag adapted for marketing and formed of material capable of being 100 rolled and folded comprising a body including opposite side portions provided with means to facilitate gripping the bag, each side portion having an inspection aperture therein and said apertures being in alignment to permit the observer to see entirely through the bag, and flexible transparent sheets covering said opening for preventing articles within the bag from falling out. 105

In testimony whereof I hereunto affix my 110 signature.

WILLIAM H. KNIEP.
